Primary Examiner — Darlington Ly*Assistant Examiner* — D. Ryan Tisdale(74) *Attorney, Agent, or Firm* — Vichit Chea(57) **CLAIM**

The ornamental design for a vehicle wheel, as shown and described.

DESCRIPTION

FIG. 1 is a front elevational view of a vehicle wheel showing our new design; and,

FIG. 2 is a perspective view thereof.

The ghosted or low contrasted areas in the drawings illustrated portions of the vehicle wheel that form no part of the claimed design.
